UNITED STATES PATENT OFFICE.

FRED LACROIX, OF NEW YORK, N. Y., ASSIGNOR OF ONE-HALF TO ALICE M. KETCHUM,
OF NEW YORK, N. Y.

TELEPHONE.

1,245,929.

Specification of Letters Patent.

Patented Nov. 6, 1917.

Application filed April 14, 1916. Serial No. 91,017.

To all whom it may concern:

Be it known that I, FRED LACROIX, a citizen of the United States, and a resident of New York, in the county of New York and 5 State of New York, have invented certain new and useful Improvements in Telephones, of which the following is a description.

In the sending of telephone messages ordinarily the charge is made against the subscriber at the sending end of the line, and the unauthorized use of the instrument in sending messages has caused considerable friction between the subscriber and the company in adjusting his account. The object 15 of the present invention is to provide means whereby a subscriber can control the sending of messages through his instrument without interfering with the receipt of incoming messages.

Locking devices have been provided for securing the instrument against unauthorized use, but such devices are objectionable as they prevent the use of the instrument 25 to receive incoming messages, as well as to prevent the initiation of out-going messages. The present invention avoids this objectionable feature, for the control only extends to the initiation of out-going messages, 30 and in no way effects the receipt of incoming messages and the reply to the same.

The invention consists in the novel construction and arrangement of parts herein-after described, pointed out in the appended 35 claims, and illustrated by the accompanying drawing.

The figure in the drawing is a diagrammatic representation of a subscriber's telephone embodying the invention.

40 Leading from the central station to the subscriber's station are the lines 1 and 2 forming a normally closed ringing circuit through the bell *a* and coil of the magnet *b*. Leading from the line 2 is the branch 3 forming an electric path through the transmitter *c* and the receiver *d*, the continuity 45 of this path being controlled by the switch-hook of the receiver in the usual manner. The branch 3 terminates in the switch *e* positioned to be attracted by the electro-magnets *b* and *f* when the latter are energized. The switch is normally pulled away from the magnets by the spring *g*. The coil of the magnet *f* terminates at one end 50 in the contact 4 in a position to engage the switch *e* when the latter is moved by the energized magnets, and at the other end the coil terminates in the line 1. Bridging the magnets and the switch *e* is the line loop 5 leading from the branch 3 to the line 1. 60 In the line loop 5 are the contacts 6 adapted to be closed by the key *h*. A casing *i* 65 encloses the magnets *b*, *f*, the switch *e*, and the contacts 6, and is provided with a hole to admit the key *h*.

The operation is as follows: When the ringing circuit is closed at the central station through the wires 1, 2, the call bell *a* is sounded at the subscriber's station and the magnet *b* is energized and the switch *e* 70 is moved to engage the contact 4 and thereby closes the speaking circuit at that point. In responding to the call the subscriber lifts the receiver and the upward movement of the released switch-hook completes the speaking circuit through the line 3 at that point. The operator at the central station on obtaining the response through the lifting of the receiver at the subscriber's station, cuts out the alternating or ringing current and 75 simultaneously turns in the direct or speaking current. When the ringing current is broken the magnet *b* is deenergized, but the immediate passage of the direct current through the magnet *f* causes the latter to 80 hold the switch *e* against the contact 4 and sustains the speaking circuit at that point. When the receiver is returned to its hook the speaking circuit is broken, and as the magnet *f* is deenergized the switch *e* is 85 pulled away by its spring and the speaking circuit is also broken at that point. The initiation of calls at the central station is not affected by the subscriber's controlling means 90 at his station.

Should it be desired to initiate a call at the subscriber's station the key *h* is positioned to close the break between the contacts 6 in the bridging loop 5. When the receiver is lifted the upward movement of 95 its hook completes the circuit with the central station through the leads 1, 2, the branch 3, and the bridging loop 5. On receiving the signal the operator makes the usual connection with the other subscriber 100 and the line is operated in the usual manner.

Should the subscriber desire to prevent the sending of messages from his station he removes the key *h* to break the circuit through the bridging loop 5. When this 110

is done no circuit can be established between the subscriber's instrument and the central station. Should the transmitter be lifted and its hook moved to close the circuit at 5 that point, the circuit to the central station would still be incomplete through the break between the contacts 6, and by the break caused by the switch *e* being pulled away from the contact 4. With the key *h* in place 10 to close the break between the contacts 6 the circuit to the central station could be readily established. By controlling the handling of the key *h* the subscriber can control the sending of messages from his station. The 15 key and key-hole can be provided with the usual guards to prevent the use of false keys.

Having thus described my invention, what I claim and desire to secure by Letters Patent is:

1. In a telephone, a circuit from the central station including at the subscriber's station a normally closed ringing circuit and a normally open talking circuit, a normally 25 open switch in the talking circuit, an electromagnet in the ringing circuit when energized operating to move said switch to close the talking circuit at that point, a second electromagnet in the talking circuit 30 when energized operating to hold said switch to close the talking circuit at that

point, a line loop bridging the talking circuit around said switch and around the electromagnet in the talking circuit, and removable means for making and breaking the 35 talking circuit through the bridging loop.

2. In a telephone, a circuit from the central station including at the subscriber's station a normally closed ringing circuit and a normally open talking circuit, a normally 40 open switch in the talking circuit, an electromagnet in the ringing circuit when energized operating to move said switch to close the talking circuit at that point, a second electromagnet in the talking circuit when 45 energized operating to hold said switch to close the talking circuit at that point, a line loop bridging the talking circuit around said switch and around the electromagnet in the talking circuit, said bridging loop having 50 separated contacts, a casing inclosing the electromagnets, switch and contacts of the bridging loop and provided with a key-hole, and key adapted to be inserted through the key-hole into the casing to electrically connect the contacts of the bridging loop.

In testimony whereof I hereunto affix my signature in the presence of two witnesses.

FRED LACROIX.
